REFRIGERATOR DOOR STRUCTURE

Frank D. Peltier, Indianapolis, Ind., assignor, by
mesne assignments, to Philco Refrigerator
Company, Philadelphia, Pa., a corporation of
Delaware

Application May 2, 1938, Serial No. 205,467

3 Claims. (Cl. 20—35)

This invention relates to improvements in the structure of refrigerators, and more particularly to the structure of a closure or door for refrigerators of domestic type.

An object of the invention is to provide an improved refrigerator door of a so-called "flat" type, no part of which projects within the refrigerator chamber, the door being of metallic sheet construction wherein the sheets are enameled or otherwise treated to give a pleasing appearance to the finished door as well as to facilitate surface cleaning thereof, the door comprising inner and outer facing sheets or panels and heat-insulating material therebetween, the sheets being assembled together in an improved manner, through insulating gaskets arranged to preclude conductive heat-transfer between the sheets.

Another object is found in the provision in a refrigerator door construction as above indicated, of heat-insulating gaskets which serve to air-seal the refrigerator at the door opening upon closure of the door, the gaskets further being assembled to the door in a manner to provide thereby, heat-insulating spacing of the door sheets.

A further object is to provide an improved form of sealing gasket for refrigerator doors of the type noted, the gasket being comprised of a resilient, hollowed bead structure engageable with the cabinet door jamb upon closure of the door, and a resilient shank portion adapted for assembly engagement with spaced flanges on the inner panels of the door, the shank serving in cooperation with securing elements, to connect the inner panels in the assembly of the door.

Other objects and advantages provided by the improved door construction will appear readily from the following description and from the accompanying drawing, in which:

Fig. 1 is a fragmentary, transverse section of a refrigerator structure embodying the features of the invention; Fig. 2 is a reduced plan view of a refrigerator door constructed according to the present invention, the view thereof being directed toward the inner side of the door; Fig. 3 is a plan view of the door similar to that of Fig. 2, but the view thereof in this instance being directed toward the outer side of the inner sheets of the door whereby to illustrate the manner of connecting the inner sheets by the gasket and securing elements; Fig. 4 is an enlarged, fragmentary transverse section of the door, as viewed from line 4—4 in Fig. 3, and Fig. 5 is an enlarged, fragmentary section thereof, as viewed from line 5—5 in Fig. 3.

Referring to the drawing by suitable reference characters, there is shown a portion of a refrigerator cabinet, the cabinet structure including inner sheathing plates 10 and outer plates 11 which enclose suitable insulating material 12. 5 The plates are connected at the cabinet opening 13 which gives access to the cabinet chamber 14, by breaker strips 15 which may be of heat-insulating material. The cabinet is provided at the door opening 13, with a door or closure structure 16 suitably hinged thereto (not shown), the door being of the so-called "flat" type and comprised of an outer face sheathing or panel 17 of metallic sheet material, an inner face sheathing or panel 18 and a panel strip 19 around the 15 inner edge portion of the door, the latter panels being formed from suitable sheet material. All of the panels may be enameled or similarly treated for the sake of appearance and also to facilitate surface cleaning thereof. It is to be 20 noted that no part of the door projects within the cabinet opening 13, while the inner panel 18 is alone directly exposed to the chamber 14.

In the construction and assembly of the door, the peripheral end portion 20 of outer sheathing 25 17 is turned in as shown in Figs. 1 and 4, and further the marginal edge of the turned portion is formed to provide a flange 21 which is directed inwardly of the door structure. The panel strip 19 is arranged so that its outer marginal portion 22 overlies in parallel adjacence, the flange 21. The edge of marginal portion 22 is formed to provide a flange 23 directed toward the flange 21. Seated between the flange 21 and marginal portion 22 is a flanged base 24 of 30 a heat-insulating gasket 25 which may be formed from flexible rubber or other similar material. The gasket base 24 serves to maintain the described spacing of the panel strip margin 22 from the outer sheathing plate flange 21, in the assembly connection of those elements effected preferably by screws 26. Extending from the gasket base 24 and formed integrally therewith, is a bead 27 which overlaps the flanged edge 23 of facing strip 19 and is curved inwardly over 45 the surface of the strip marginal portion 22. The gasket preferably is of one-piece construction, extending peripherally about the door as shown in Fig. 2, the curved bead 27 of which overlies the heads 28 of the panel fastening 40 screws 26 so as to conceal them. The gasket base 24 interposed between the flange 21 of sheathing 17 and the marginal portion 22 of strip 19 serves to maintain the spacing of these 50 portions, to preclude heat-conduction therebe- 55

5 The only metallic, heat-conductive contact of the flange 21 and marginal portion 22 is through the assembly screws, but the heat-conductive capacity thereof is small and hence for practical purposes, negligible. It is to be noted that by reason of the engagement of the flanged portion of gasket base 24 with the flange 23 on the edge of marginal portion 22, the gasket is effectively retained in assembly with the door structure.

10 The inner margin 30 of the strip 19 is formed to provide a flanged edge 31 which is turned inwardly of the door assembly. The inner panel 18 is provided with a similarly inturned flange 32 along the margin 33 thereof, the flange being of angulate form providing a surface 34 of bevel aspect, for a purpose later appearing. In the assembly relation of the inner panels 18 and 19, the respective flanges 31 and 32 are spaced as shown in Fig. 4, and cooperate in forming a recess for the reception of a shank portion 35 of a resilient gasket 36 formed of rubber or other suitable heat-insulating material. It will be noted (Fig. 5) that the free ends 37 of the flanges 31 and 32 are flared in the direction shown, this for a purpose which will later appear.

15 Formed as an integral part of the shank 35 is a resilient bead structure 38 which comprises a hollow, substantially cylindrical portion 39 and a hollow, substantially rectangular portion 40 projecting laterally of the portion 39 and upper end of shank 35. The portion 39 seats against the flange bevel 34, while the portion 40 engages and seats upon the margin 30 of panel 19. The gasket 36 which may be a one-piece structure, extends peripherally about the door and inwardly adjacent the outer gasket 25, as appears in Fig. 2. The panels 18 and 19 are connected together with the gasket shank 35 therebetween, by a

20 plurality of clamping elements or bolts 41. The panel flanges 31 and 32 are provided with registering apertures 42 in each of which is seated a flanged washer 43 formed of a suitable heat-insulating material, as rubber. A bolt 41 is projected through the washers and a bolt-receiving aperture 44 in the gasket shank 35, the bolt head 45 engaging one of the washers while the threaded end 46 of the bolt which projects beyond the opposite washer, is provided with a securing nut 47 and washer 48. It is preferred to form the gasket shank 35 in a manner to provide hollowed portions or closed chambers 49 of any desired section, as substantially rectangular in the present example, the chambers preferably extending 25 throughout the length of the gasket. These chambers serve to increase the resiliency and compressibility of the shank, so that in the assembly of the panels 18 and 19 the shank disposed between the panel flanges 31 and 32 may be compressed to a considerable degree, and further by reason of the flared ends 37 of the flanges 31 and 32, the end 50 of the gasket shank 35 will become outwardly flared as the shank is compressed between the flanges. This serves in 30 cooperation with the panel securing bolts 41, to retain the gasket in assembly with the door.

35 The gasket shank 35 and washers 43 being of a heat-insulating material, serve to prevent heat-conduction between the inner panels 18 and 19, since by reason thereof there is no contact between the flanges 31 and 32, nor between the flanges and the securing bolts 41, the latter by

reason of the flanged washers 43 as clearly appears in Fig. 4. Moreover, the gasket shank 35 being of resilient construction and interposed between the panel flanges 31 and 32, serves to accommodate or absorb slight irregularities in the size or shape of the panel 18 and/or 19 as may occur in the manufacture thereof.

40 As shown in Figs. 4 and 5, the gasket beads 39 and 40 are positioned to engage and overlap the margin of the cabinet door opening and the breaker strips 15 upon closure of the door, the resiliency of the beads by reason of their chambered construction, permitting compression thereof between the cabinet and door to effect a positive air-seal of the door at the cabinet opening. Moreover, the gasket shank 35 together with the insulated washers 43 at each bolt 41, serve effectively to heat-insulate the inner panel 18 which is directly exposed to the refrigerator chamber 14, from the panel strip 19, and from the outer panel 17 through the insulating gasket 25.

45 From the foregoing, it will appear that the door panels 17, 18 and 19 are assembled in a manner to prevent heat-conduction between them, thus effecting a heat-insulated door structure, while the gasket 36 provides an effective air-seal of the door at the cabinet opening when the door is in closed position. In the assembly of the door, the space enclosed by the panels is filled by a heat-insulating material 51 of any suitable type, which further heat-insulates the door.

50 Having described a preferred embodiment of the invention, the elements of which may be altered or modified within the scope of the invention, I now claim what I desire to secure by Letters Patent of the United States.

I claim:

1. In combination, a pair of sheet-like members having relatively spaced margins, flanges on said margins disposed in substantially parallel adjacence, a resilient gasket comprising a portion seated between said flanges and a bead portion projecting beyond the sheet members and having a plurality of chambers therein, said bead engaging one of said flanges and the margin of one of said sheet members, and means protecting through said flanges and gasket portion therebetween, for securing thereof in assembly.

2. In combination, a pair of panels having relatively spaced margins, flanges on said margins disposed in substantially parallel adjacence, a resilient gasket structure comprising a chambered portion seated between said flanges and a bead portion projecting beyond said panels, said bead portion engaging one of said flanges and the margin of one of said panels, and panel securing means extending through said flanges and gasket portion therebetween.

3. In a door structure of the type described, an outer metallic panel, inner metallic panels spaced from said outer panel, means connecting said outer panel to one of said inner panels, the opposite margins of said inner panels being relatively spaced and provided with flanges, and means connecting said inner panels through said flange said means including a heat-insulating gasket of a resilient, chambered construction, interposed between said flanges and securing means extending through said flanges and gasket.

FRANK D. PELTIER.
